UNITED STATES PATENT OFFICE.

SAMUEL C. BOND, OF WILMINGTON, DELAWARE, ASSIGNOR TO BOND BOTTLE SEALING COMPANY, OF WILMINGTON, DELAWARE, A CORPORATION OF DELAWARE.

APPARATUS FOR SEALING AND CAPPING BOTTLES.

1,002,816.

Specification of Letters Patent.

Patented Sept. 5, 1911.

Application filed April 10, 1909, Serial No. 489,112. Renewed April 5, 1911. Serial No. 619,172.

To all whom it may concern:

Be it known that I, SAMUEL C. BOND, residing at Wilmington, in the county of Newcastle and State of Delaware, a citizen of the 5 United States, have invented or discovered certain new and useful Improvements in Apparatus for Sealing and Capping Bottles, of which improvements the following is a specification.

In Letters Patent No. 898,959 and No. 899,004, dated September 15, 1908, I have described and claimed certain improvements in sealing bottles, said improvements consisting generally stated in seating a flanged 15 cap on a bottle and by pressure applied to the flange in a direction substantially parallel with the axis of the bottle, causing said flange to grip the bottle and firmly hold the cap in position thereon. In thus bending 20 the flange into engagement with the bottle a crimping or folding of the metal necessarily occurs, and if some portions of the flange are weaker than others such crimping will be localized along the weaker portions, 25 and consequently the cap will be locked to the bottle only where the crimps occur.

The invention described herein has for its object a mechanism whereby a substantially uniform crimping of the flange and the forcing of the crimps into locking engagement with the bottle may be effected.

The invention is hereinafter more fully described and claimed.

In the accompanying drawings forming 35 a part of this specification, Figure 1 is a sectional view of a sealing head of the type shown in the patents referred to, and embodying my improvement; Fig. 2 is a detail view showing a cap and the cap seating and 40 locking fingers at the beginning of the capping operation; Figs. 3, 4 and 5 are views partly in elevation and partly in section illustrating progressive steps in securing the cap to the bottle; Fig. 6 is a sectional view 45 on a plane indicated by the line VI—VI Fig. 5, looking in the direction of the arrow a; Fig. 7 is a sectional view of a different type of capping head but embodying my improvement; Figs. 8, 9 and 10 are plan 50 views of modifications of my cap-applying device, and Fig. 11 is a detail view of the block carrying the cap-sealing members showing the shoulder which serves as a support for such locking fingers or struts.

55 It will be readily understood by those

skilled in the art that any suitable form of mechanism may be employed for shifting the sealing head or the bottle supporting table or both relative to each other.

The head 8 is formed in part by shell 11, 60 having an enlarged lower portion for the reception of the radially slotted annular block 12, which is held in position by the annular plug 13, removably secured to the shell 11. The inner walls of the plug are made flaring 65 so as to serve as a guide for the bottle. Struts or fingers 14 are so pivotally supported in the slots in the block 12, which has an internal diameter somewhat greater than the greatest diameter of the cap, that the 70 portion of said struts designed to engage the cap will be in a plane below the plane of the pivotal points of the struts, and will lie in a circle having a diameter intermediate 75 of the greatest and least external diameters 75 of the cap. These struts are held from outward radial movement after engagement with the cap, so that when their inner ends are shifted relatively to their pivotal points, 80 by engagement with the flange of the cap, such ends will move in toward a common center, until they bear against the side walls of the cap as hereinabove described. These struts are so constructed and arranged within the block 12 as to have a sufficient outward radial movement when a cap is thrust 85 in between them to allow the insertion of caps differing somewhat in diameter. These struts are preferably V-shaped, and are pivotally supported at or adjacent to their 90 apices. In the construction shown their apices project between rings 15 arranged in grooves formed in the outer periphery of the block 12, said rings being split to permit of their easy insertion into the grooves. 95 While the normal position of the struts may be determined by any suitably arranged stop, against which the struts will move after a cap has been secured on a bottle, it is preferred to control the return movements 100 of the struts by means of a sleeve 16 freely movable in the shell 11, and provided at its lower end with a flange 17 adapted to project between the legs of the struts. This sleeve normally rests on a shoulder 105 28 formed on the inner wall of the block 12, and when in this position the upper legs of the struts will rest on the flange 17, and thereby hold the struts in proper operative 110 position. This construction whereby the 113

struts are held in proper normal position is preferred, as it will perform another very important function, *i. e.*, insure the simultaneous movement or operation of all the struts.

It has been found in practice that in case portions of the flange *a* of the cap are weaker either by reason of the metal being thinner at such points, or for some other cause, there will be a localization of the crimps necessarily formed in the flange *a* when the latter is bent from position at right angles to the axis of the cap down to or approximately to parallelism with such axis, in locking the cap to the bottle. When the crimps are thus localized the stronger portions of the flange will be simply bent down without any material crimping action, upon the bottle, and will not fully engage under the head of the bottle. In order to prevent any such localization of the crimps from any cause and to insure a uniform crimping at all points, provision is made for a preliminary crimping of the flange before any material bending of the same into locking engagement with the bead on the bottle can occur. To this end a portion of the fingers or struts are made a little longer than the others, so that such longer struts will engage the flange in advance of the others, and by reason of such engagement will partially crimp or dent the flange as indicated at *b* before the flange as a whole has been bent or materially turned down toward locking engagement with the bead of the bottle. After this crimping action by the fingers or struts 14, the shorter fingers or struts 14^a will come into engagement with the flange at points intermediate of the crimps or bends produced by the struts 14. As both series of fingers or struts have the portions engaging the flange lying in a common circle, it will be evident that as the bending progresses the portions of the cap in contact with the struts 14 will be bent to such an extent that the struts will no longer bear upon them in a direction to force them in under the bead and that thereafter the movement of the portions *a* into locking engagement with the bead will be caused by the pressure of the struts 14^a upon the portions *c* of the flange intermediate of the portions *b*. This progressive action of the two series of fingers is clearly illustrated in Figs. 3, 4 and 5. In Fig. 3 the preliminary crimp *b* is clearly shown, the part *c* intermediate of such crimps being practically in normal position or in the position occupied by the flange before the cap has been pressed upon a bottle. In Fig. 4 the portion *c* has been bent down and in its movement coacts with the struts 14 to force the portion *b* of the flange partially under the bead *d* of the bottle. When the parts of the flange have reached the position shown in Fig. 4, the struts 14 will

merely slide along the portions *b* and not exert any downward pressure thereon, but the struts 14^a will continue to bear down and force the portions *c* inward, and thereby press the portions *b* more tightly under the bead *d*. The action of the struts 14^a on the part *c* will be such as to force the portions *c* to a greater or less extent under the bead *d*, but not to the extent to which the portions *b* have been forced by the pressure of the struts 14^a on the portions *c*.

By reason of the preliminary crimping imparted by the series of fingers or struts 14, the crimps will be uniformly distributed throughout the entire circumference of the flange, and there will not be any material localization of the crimps.

In the construction shown in Figs. 1 to 6, inclusive, the seating of a cap on a bottle is effected solely by the pressure exerted by the fingers or struts on the flange as clearly set forth in the Letters Patent hereinbefore referred to. As shown in Fig. 7 my improvement can be applied to that form or type of machine in which the seating of the cap is effected by a plunger and the bending of the flange into locking engagement with the bottle is effected by devices operative independent of the plunger. In this form or type of machine, the flange bending device may consist of a ring 18 either integral or formed in two or more sections, as shown in Figs. 8, 9 and 10. On the underside of this ring are formed shoulders or projections 20 preferably V-shaped which will operate to effect the preliminary crimp corresponding in operation to the series of fingers 14 heretofore described. These projections are made of such a height that as soon as they have effected the crimping of the parts *b*, the portions 2 of the ring intermediate of the projections will come into operation and operate on the portions *c* intermediate of the bent portions *b*. These rings are made of an internal diameter a little greater than the diameter of the body of the cap to which they are to be applied, so that they would readily pass down over the cap into engagement with the flange, and can be withdrawn after the flange has been bent into locking engagement with the bottle. On account of the variations in the external diameter of the bead portion of the bottles, it is preferred that the rings should be made in sections as shown in Figs. 9 and 10, and that such sections should be yieldingly held in proper position by a spring 22 of any suitable form or construction. In the type of machine shown in Fig. 7 this ring is supported in a head 23 and held in place by an annular block 24, the plunger 25 operating through such annular block to press the cap into sealing engagement with the mouth of the bottle.

No claim is herein made for the method

described for applying sealing caps to bottles, as such subject-matter is claimed in an application filed by me December 7, 1908, Serial No. 466,376.

5 I claim herein as my invention:

1. As a means for applying caps to bottles, an annular tool provided with radially movable portions adapted to crimp or bend the flange of a cap at intervals and with 10 other portions adapted to bear on the flange at points intermediate of the bends or crimps.

2. A bottle capping machine having in combination a series of radially arranged

fingers adapted to engage the flange of a cap 15 and a second series of fingers adapted subsequently to engage the flange of the cap at points adjacent to those operated on by the first series, both series of fingers being movable outwardly at the beginning of their 20 operation.

In testimony whereof I have hereunto set my hand.

SAMUEL C. BOND.
